CLAIM

The ornamental design for a portable barbecue grill, as shown and described.

DESCRIPTION

FIG. 1 is a front-top perspective view of a portable barbecue grill showing our new design;

FIG. 2 is a front view of the portable barbecue grill of FIG. 1;

FIG. 3 is a side view of the portable barbecue grill of FIG. 1, both side views being identical;

FIG. 4 is a top view of the portable barbecue grill of FIG. 1;

FIG. 5 is a bottom view of the portable barbecue grill of FIG. 1;

FIG. 6 is a rear view of the portable barbecue grill of FIG. 1;

FIG. 7 is a front-top perspective view of a second embodiment thereof;

FIG. 8 is a front view of the portable barbecue grill of FIG. 7;

FIG. 9 is a side view of the portable barbecue grill of FIG. 7, both side views being identical;

FIG. 10 is a top view of the portable barbecue grill of FIG. 7;
FIG. 11 is a bottom view of the portable barbecue grill of FIG. 7;
FIG. 12 is a rear view of the portable barbecue grill of FIG. 7;
FIG. 13 is a front-top perspective view of a third embodiment thereof;
FIG. 14 is a front view of the portable barbecue grill of FIG. 13;
FIG. 15 is a side view of the portable barbecue grill of FIG. 13, both side views being identical;
FIG. 16 is a top view of the portable barbecue grill of FIG. 13;
FIG. 17 is a bottom view of the portable barbecue grill of FIG. 13;

FIG. 18 is a rear view of the portable barbecue grill of FIG. 13;
FIG. 19 is a front-top perspective view of a fourth embodiment thereof;
FIG. 20 is a front view of the portable barbecue grill of FIG. 19;
FIG. 21 is a side view of the portable barbecue grill of FIG. 19, both side views being identical;
FIG. 22 is a top view of the portable barbecue grill of FIG. 19;
FIG. 23 is a bottom view of the portable barbecue grill of FIG. 19; and,
FIG. 24 is a rear view of the portable barbecue grill of FIG. 19.
